UNITED STATES PATENT OFFICE.

ALEXANDER KIRKALDY, OF BROOKLYN, NEW YORK, ASSIGNOR TO KIRKALDY ENGINEERING CORPORATION, OF NEW YORK, N. Y., A CORPORATION OF NEW YORK.

ELECTRODE.

Application filed November 20, 1923. Serial No. 675,871.

To all whom it may concern:

Be it known that I, ALEXANDER KIRKALDY, a citizen of the United States, residing in Brooklyn, county of Kings, State of New York, have invented certain new and useful Improvements in Electrodes, of which the following is a specification.

This invention relates in general to an electrolytic system for the protection of boilers, condensers and the like, and more particularly to the electrodes used in such a system.

The primary object of the invention is to construct an electrode of such parts and form, and to assemble the same in such manner that it will be more efficient in its action when used in an electrolytic system of this kind.

Another object of the invention is to have the body or distance piece of an electrode made wholly of metal with the portion projecting within the boiler of greater cross section than the diameter of the opening in the boiler, through which opening a reduced portion of said body projects.

Another object of the invention is to make the current conducting member of such form that it cannot be driven through the body member, outward from the boiler, even though the major portion of said current conducting member be destroyed by the action of the electrolyte.

Another object of the invention is to reduce to the minimum the amount of exposed insulation on the part of the electrode within the boiler.

Other and further objects, including certain features of construction and application will appear in the specification and be pointed out in the appended claims, reference being had to the accompanying drawings which show the preferred embodiment of this invention.

In an electrolytic system of this kind it is essential that the member conducting the current from the positive terminal outside the boiler shell to the anode within said boiler, be insulated both from the boiler shell and the liquid within the boiler. Heretofore electrodes made for this purpose have had their body portions, or those portions projecting within the boiler, made of insulating material, such as porcelain or some special insulating substances, but owing to

the fact that these insulations are directly exposed to the heat and water of a boiler, they have proven mechanically unsuitable for the purpose; porcelain because of its tendency to fracture under compression or by vibration and the special insulations because of their tendency to absorb water, swell and split and also the inability of these special insulating substances to withstand the heat of the modern high pressure boiler. In the present invention the supporting body or distance piece is made of any suitable metal and insulated from the boiler shell and the current conducting member for the anode with the minimum of exposed insulation within the boiler, thereby overcoming the undesirable features of the present electrodes and giving the maximum of efficiency at all times and under all conditions.

In the accompanying drawings:

Figure 1 is a side elevation of an electrode attached to a boiler.

Figure 2 is a central vertical section of the same.

Figure 3 is a partial transverse section of a standard boiler showing how the anodes are mounted.

Figure 4 is a partial sectional elevation of the same.

Referring to Figures 3 and 4 of the drawings, 1 is the shell of a boiler of one form of standard construction, 2 the tubes therein, 3 and 4 the front and rear ends of the boiler, 5 the tie bolts, 6 the heating compartment and 7 the water line.

The anode supporting means which form the essential feature of the present invention, comprises a body member or distance piece 10 of any suitable metal and projecting within the boiler the required distance to accomplish the intended purpose. The outer end of this body member is reduced in diameter to form a neck 11, said neck being externally threaded, as shown at 12. By reducing the diameter of the body in this manner a shoulder 11^a is made which aids in holding the body member in desired position when the parts are assembled. Through the body 10 is an axial opening 13 in which is placed a tube of insulation 14 of any material suitable for the purpose, but owing to its heat resisting qualities mica is preferably used. At the inner end of the

body the opening 13 is enlarged to form a recess 15 and a shoulder 16, the walls of the recess and the shoulder being covered by the tube of insulation 14. Within the tube of insulation, in the manner shown in Figure 2, is the current conducting member 17 the outer end of which is threaded as indicated at 18.

In order to properly assemble the parts the current conducting member is provided with a base 19 and preferably of the same diameter as the body member 10. On the current conducting member, above the base 19, is a head 20 which fits within the enlarged portion of the tube of insulation 14 and engages the insulated shoulder 16 of the body member. The base of the current conducting member has its inner end reduced in diameter to form a threaded projection 21 for the purpose hereinafter explained.

Located on the insulating tube 14 between the body and the base of the current conducting member, are two packing washers 24 and 25 having therebetween a plurality of sheets of mica 26 to insulate the base of the current conducting member from the body 10. On the threaded end of the current conducting member and engaging the outer end of the neck of the body, is a packing washer 27, a plurality of sheets of mica 28 and a metal washer 29. The metal washer is engaged by a nut 30 which when tightened compresses the packing washers between the base of the current conducting member and the body and at the same time compresses the packing washer 27 and mica sheets 28 firmly against the neck 11 of the body 10, lock nut 31 tending to hold said parts in the desired position. Within the outer end of the current conducting member is a set screw 32 which holds the positive terminal 33 firmly in contact with said current conducting member. Surrounding the unthreaded portion of the neck of the body and adapted to engage the wall of the opening 34 in the boiler shell, is a collar of mica 35 which serves to insulate said body from the boiler shell.

Carried on the insulating collar 35 within the boiler and in contact with said boiler, is a packing washer 36 which is engaged by a mica ring 37 in turn engaged by a metal washer 38, one face of which has the same contour as the inner surface of the boiler shell and the other surface flat to abut the shoulder 11^a on the body 10. In similar position outside the boiler shell on the insulating collar is a packing washer 39, a ring of mica 40 in contact with the packing washer and a metal washer 41 one face of which has the same contour as the outer surface of the boiler shell and rests against the mica ring. Threaded on the neck of the body is a nut 42 adapted to engage the flat side of the metal washer 41 and firmly force

said washers and mica sheets into compact position, thereby completely insulating the body 10 from the boiler shell and making a leak proof connection between the body and the shell of the boiler. To positively lock these parts against possible displacement a lock nut 43 is jammed against the nut 42.

Thus it will be seen that when the current conducting member, the insulating tube and the body 10 are united in the manner above described they form a single unit that can be readily handled when it is desired to install them in active position within the boiler.

In structures of this kind the current conducting member is always exposed after passing through the body member and is therefore subject to gradual destruction, due to the electrolytic action within the boiler. If the base or anode supporting parts are completely destroyed down to the current conducting member serious accidents may occur because said current conducting member will, by the pressure within the boiler, be driven outward through the body member. To overcome this undesirable feature the present current conducting member is provided with the head 20 larger than the opening 13, said head engaging the shoulder 16 on the body and preventing the current conducting member from being accidentally driven through the body member, whatever may happen to the exposed portions of said current conducting member.

To assemble the parts in the manner shown in Figure 2, the current conducting member has placed thereon the tube of insulation 14 and over the tube of insulation, adjacent the base, the packing washer 24, insulation 26 and the packing washer 25. The current conducting member with the insulating tube thereon is then placed within the opening 13 in the body member with the packing washers and insulation interposed between the end of said body and the base 19. Washer 27, insulation 28 and metal washer 29 are then placed over the threaded end of the current conducting member 17 and against the outer end of the neck of the body, after which the holding nut 30 is placed in position and tightened until the parts are firmly drawn together where they are permanently held by the lock nut 31. The body and current conducting members, positively insulated from each other, now form a single unit ready to be installed in a boiler. Installation is accomplished by first applying the insulating collar 35 over the neck of the body and placing the metal washer 38 against the shoulder 11^a, then the mica insulation and the packing washer 36. The neck of the body is now ready to be put

through the opening in the boiler shell followed by placing the packing washer 39, the mica insulation 40 and the metal washer 41 in position in the order named. Nut 5 42 is then tightened until the parts are drawn together and firmly held against the boiler shell, after which the lock nut 43 is jammed against the nut 42.

On the threaded projection 21 of the base 10 of the current conducting member is placed a nut 45 which engages the shoulder 46 on said base, and serves as an abutment for the vertical supporting bar 50 of the anode carrying frame, said bar being held in position 15 on the projection by a nut 47, said nut in turn being held against displacement by a lock nut 48.

In Figures 3 and 4 is shown one of the present accepted methods of suspending the 20 anodes within one of the boilers of standard construction. Herein are shown four electrodes extending through and fastened to the top of the boiler in the manner hereinbefore explained, each electrode having attached to its projection 21 a dependent supporting bar 50 of the anode carrying frame. In order to hold the supporting bars firmly 25 in the desired position they are tied together by transverse bars 51, as shown in Figure 3. Fastened to each lower transverse bar is a short dependent bar 52 which terminates in the same plane with the dependent bars 50. The anode bars 53 are attached to the end of each of these dependent bars 50 and 52 and extend from end to end of the boiler, in the manner shown in Figure 4. It will be noticed that the anode bars extend below the water level in the 30 boiler and adjacent the opening between each set of boiler tubes, in which position it has been found the best results are obtained.

In an electrolytic system for the protection of boilers, a positive low tension, direct current of low amperage and voltage is supplied from a suitable source and directly connected to the anodes, which are submerged in the boiler water. Figure 3 shows how the electrodes are connected with the positive side and the boiler shell with the negative side of a suitable source of electrical energy, as shown at 60, but in view of the fact that the electrical equipment forms no part of the present invention it is not deemed necessary to show more than is set forth in the drawings.

By referring to the drawings it will be noticed that the supporting body member is made wholly of metal, but at all times and under all conditions remains "neutral," due to the fact that it is insulated from the positive current conducting member and from the boiler shell and cannot, even though in contact with the electrolyte, conduct current back to the boiler shell, nor can a short circuit occur through said body member.

By having the supporting body made of metal the life of the electrode supporting parts is materially lengthened, because the metal offers a definite heat resisting and moisture proof value. It will be observed 70 that in the construction of the present electrode support the least possible amount of insulation is exposed within the boiler and where exposed an insulation is used that is impervious to the heat and moisture of any 75 make of boiler.

While I have shown the electrode as applied to a particular form of boiler, it should be understood that the same is capable of being applied to any form of 80 boiler, condenser, tank or the like, and while I have shown and described the preferred embodiment of my invention obviously modification may be made within the spirit of the appended claims. 85

I claim:

1. In an electrolytic system for the protection of boilers, an electrode having in combination a body member of non-insulating material to project through a boiler shell 90 into exposed position within the boiler and insulated therefrom, and a current conducting member extending through said body member and insulated from said body member and the boiler shell. 95

2. In an electrolytic system for the protection of boilers, an electrode having in combination a body member of non-insulating material projecting into and insulated from a boiler, a current conducting member extending through said body member and insulated therefrom, means for uniting the current conducting member and the body member, and means for attaching the body member to the boiler shell. 100

3. In an electrolytic system for the protection of boilers, an electrode having in combination a metal body member projecting through and exposed within a boiler, the portion of said body within the boiler being larger in cross section than the portion of said body passing through the boiler shell, a current conducting member extending through and insulated from said body, and means for uniting said current conducting member and body member. 110 115

4. In an electrolytic system for the protection of boilers, an electrode having in combination a metal body member projecting through and within a boiler and provided with a longitudinal opening therethrough and a recess in the inner end thereof larger than the longitudinal opening, a current conducting member extending through and insulated from said body member and provided with a head adapted to fit within the recess in said body member, means for uniting said current conducting member and body member, and means for attaching said body member to the boiler shell. 120 125 130

5. In an electrolytic system for the protection of boilers, an electrode having in combination a metallic body member, a current conducting member extending through said body member and insulated therefrom said body member being insulated from the shell of a boiler and the electrolyte therein, means for holding said current conducting member within the body member, and means for attaching said body member to the boiler shell.
6. In an electrolytic system for the protection of boilers, an electrode having in combination a metallic body member adapted to be attached to and insulated from a boiler, a current conducting member extending through said body member and insulated therefrom, means for uniting said current conducting member and body member, and means on the current conducting member for supporting an anode within the boiler.
7. In an electrolytic system for the protection of boilers, an electrode having in combination a metallic body member one end of which is reduced in cross section to project through the shell of a boiler, insulating material between said reduced body portion and the boiler shell, a current conducting member extending longitudinally through said body member, insulating material between said current conducting member and body member, means for uniting said body member and current conducting member, means for attaching the body member to the boiler shell, and means on the current conducting member for supporting an anode within the boiler.

ALEXANDER KIRKALDY.
